INDENTING MACHINE

Robert N. Sandberg, Beverly, Mass., assignor to
United Shoe Machinery Corporation, Flemington, N. J., a corporation of New Jersey

Application July 24, 1942, Serial No. 452,241

55 Claims. (Cl. 12—32)

This invention relates to indenting machines and is herein shown as embodied in a machine for making ornamental indentations or imitation stitches in the top face of a welt secured to the outwardly projecting marginal portion of a sole attached to a welted shoe or, in the absence of a welt, for making such indentations in the top face of the projecting marginal portion of the sole itself.

The primary object of the invention is to provide an indenting machine of novel construction and operation by which the work is operated on more rapidly and uniformly than heretofore, regardless of the type of work or variations in the work thickness.

It is a further object of the invention to provide an indenting machine having simplified mechanism for actuating the operating instrumentalities of the machine, including the indenting tool, so as to indent and feed the work as well as burnish the indented portion of the work. Moreover, it is an object of the invention to reduce to a minimum noise and vibration both of which are usually the result of the simultaneous operation of a series of cam-operated trains of mechanism for actuating the various operating instrumentalities of the machine or imparting various motions to one of these operating instrumentalities.

A still further object of the invention is to provide a satisfactory work-feeding movement, preferably a continuous work-feeding movement, in machines of the present type, and for so constructing and arranging the various operating instrumentalities of the machine that they do not tend to retard or otherwise to disturb the work feed but, on the contrary, participate in that feed, if necessary.

With the above in view, the illustrated machine, which has an indenting tool and a support for the tool, is provided in accordance with one feature of the invention, with a single mechanism, preferably an eccentric-operated or crank-operated mechanism for continuously moving the tool support in a closed orbital path heightwise and transversely of the machine so as to impart to the tool a work indenting and a work feeding motion. In particular, upon downward movement of the tool support, the tool is caused to impinge upon the top surface of the welt and to indent that surface, whereupon, as a result of the succeeding movement of the tool support in the direction of feed, the tool is moved in that direction while remaining in contact with the work and, in case of additional feed instru-

mentalities being provided, the tool is thus caused to participate with such other instrumentalities in the feeding of the work. This manner of tool operation is particularly advantageous in view of the resulting reduction of noise and vibration as well as the lessening of wear and tear in spite of the increase in speed. As illustrated, the indenting tool is supported on a front eccentric strap which is actuated by an eccentric secured on a continuously rotating shaft.

In accordance with another feature of the invention, the illustrated machine is provided with improved mechanism for imparting burnishing motions to the tool and to that end a rear eccentric strap is provided to move parallel to and in a direction opposite to the movement of the above-mentioned front eccentric strap. This rear eccentric strap also is actuated by an eccentric mounted on the same rotating shaft as the first-mentioned eccentric and at the rear thereof and, furthermore, this rear eccentric carries a cam which engages the tool and imparts repeated burnishing motions to it.

A still further feature of the invention resides in the provision of means for predetermining the depth of penetration of the tool into the surface of the work, hereinafter termed the indentation depth, and this particular means is adjustable in accordance with the type and thickness of work operated upon. To that end the tool is carried in the illustrated construction, by an arm which is mounted on the tool-supporting front strap for movement relatively thereto and which, upon downward movement of the strap, is arranged to engage an adjustable stop serving to terminate the downward movement of the arm and, accordingly, to determine the indentation depth, while permitting continued downward movement of the strap. As previously stated, the tool supporting strap not only moves heightwise of the machine but also transversely of the machine in the direction of feed and this latter transverse movement occurs while the tool is in engagement with the work. By reason of the fact that the tool-carrying arm is mounted on the strap, the arm as well as the tool is constrained to move with the strap in the direction of feed, thereby imparting to the tool a work feeding motion.

In indenting machines of the above-defined type provided with work-supporting tables, it is customary to mount the work table for movement heightwise of the machine so as to enable the operator to insert the work in the machine as well as to enable the work table to accommodate different thicknesses of the work. Moreover, in

well-known machines of this type, provision has been made for locking the table in adjusted position so as to prevent the table from yielding in a downward direction under the work-impinging impact of the tool. In accordance with a further feature of the invention, the illustrated machine, which also has a heightwise adjustable table and mechanism for locking the table in adjusted position, is provided with mechanism for intermittently releasing the table during the machine operation to enable the table to be adjusted to accommodate different work thicknesses. This lock-releasing mechanism is actuated by the tool-operating mechanism. In particular, the previously mentioned rear eccentric strap carrying the cam for imparting burnishing movements to the tool also carries the lock-releasing mechanism and the arrangement is so that the two eccentrics for actuating the two straps are, diametrically opposite to each other so that the straps move in opposite directions with the result that when the tool is elevated into its operative position by the front strap, the table-locking mechanism is released by reason of the downward movement of the rear strap.

In an attempt to insure a more satisfactory work-feeding motion, well-known indenting machines have been provided with positively rotated work-supporting tables and, accordingly, the illustrated machine is also provided with mechanism for positively and continuously rotating the work table at a uniform peripheral velocity. To promote still further a satisfactory feed motion of the work, the illustrated machine is provided, in accordance with another feature of the invention, with a presser foot movable heightwise and transversely of the machine, the presser foot being caused during a certain period of one cycle of operation to clamp the work against the rotary table and thus to cause the work to be fed forward. The arrangement is such that the indenting tool and the presser foot alternately clamp the work against the rotary table so as to accomplish a continuous feeding of the work. Specifically, immediately before the termination of the feed movement of the indenting tool, the presser foot is depressed to clamp the work against the continuously rotating table and to continue the work feed while the indenting tool is on its return stroke.

The illustrated machine is also provided in accordance with a still further feature of the invention, with a novel treadle mechanism designed to be of use in performing or initiating two different operations. As illustrated, the treadle mechanism comprises a frame mounted for movement about a horizontal axis and a cylindrical treadle member rotatably mounted in aligned bearings provided in the frame. The rotary treadle member carries at its front end a tread plate which, depending upon the portion of the tread plate to which pressure is applied, may be used in depressing the frame so as, for example, to elevate the work support into its operative position, or to rotate the treadle member so as, for example, to change the rate of speed of the indenting tool, or both operations may be performed simultaneously or in the reverse sequence. It is to be understood that the treadle mechanism is not limited in its utility to indenting machines of the illustrated type nor, indeed, to indenting machines, but may be used in connection with other machines for operating on work parts in which a plurality of operations is to be initiated or performed by treadle-controlled mechanism.

The above and other features of the invention, including various novel details of construction and combinations of parts, will now be more particularly described with reference to the accompanying drawings and will be pointed out in the claims.

In the drawings,

Fig. 1 is a front elevation of a welt-indenting and burnishing machine in which the present invention is embodied;

Fig. 2 is a plan view of a presser foot mechanism with which the machine illustrated in Fig. 1 is provided;

Fig. 3 is a right-hand side elevation of the machine;

Fig. 4 is a front view, partly in section, of certain work-handling instrumentalities and operating mechanism associated therewith;

Fig. 5 is a left-hand side view of a portion of mechanism for supporting the work table;

Fig. 15 is a plan view of a treadle mechanism of the machine;

Fig. 16 is a detail view, partly in section, illustrating the mounting of the work table on its supporting assemblage;

Fig. 17 is a detail view illustrating the connections between the work table supporting assemblage and mechanism for setting an indenting tool stop;

Fig. 18 is a front elevation, in section, of part of the table-locking mechanism; and

Fig. 19 is a plan view, in section, of the table support, the table lock, and the stop mechanism for the indenting tool.

The illustrated welt-indenting and burnishing machine has a lower frame portion 20 (Figs. 1 and 3) secured to a suitable base 22. Mounted upon the lower frame portion 20 is an upper frame portion or head 24 provided with an overhang 26 (Fig. 3). Secured to the head 24 is a front cover 28 or apron which serves to house or

shield certain movable machine parts. The front portion of the overhang 26 is anchored to the portion of the head 24 immediately beneath it by a vertical pin 30 the ends of which are secured in the head 24 and the overhang 26, respectively, by screws 32.

The principal operating or work-handling instrumentalities of the illustrated machine comprise a work-supporting table 34, an indenting tool 36, a guard member 38, and a presser foot 40. The work-supporting table 34 (Figs. 1 and 3) is mounted both for movement heightwise of the machine and for rotation about an inclined axis. The welt-indenting and burnishing tool 36 (Figs. 3, 8 and 9) is shaped roughly in the form of a hammer and provided with two elongated teeth arranged in juxtaposition on its work-engaging surface. The tool is mounted, as will be described, for movement heightwise and transversely of the machine so that the tool has a work indenting and a work feeding motion. Moreover, the tool is mounted for rotary motion in a direction at right angles to the vertical plane in the line of feed F (Fig. 1) as well as for movement along the line of feed. The guard member 38 (Figs. 1, 3 and 9) serves to protect the upper portion A (Fig. 9) of a shoe, presented to the machine for the purpose of having its outsole B or a welt thereon indented, against possible damage which may result from the indenting and burnishing action of the tool 36. The guard member 38 also serves as a gage determining the position of the work heightwise of the machine. Finally, the presser foot 40 (Figs. 2, 4 and 8) serves, by engaging the marginal portion of the outsole B and clamping it against the rotary table 34 during a certain period of a cycle, to assist in the feeding of the work.

The driving mechanism of the machine comprises the following principal parts: A motor 42 (Fig. 3), the operation of which may be initiated or terminated by a suitable switch (not shown), is secured to a bracket 44 bolted to the lower frame portion 20. Secured to the end of the rotor shaft of the motor is a pulley 48 the rotary motion of which is transmitted by a belt 48 to a pulley 50 secured to one end of a main shaft 52 mounted in suitable bearings in the machine frame. Secured on the main shaft 52 is a second pulley 54 which is in driving engagement by means of a belt 56 with a pulley 58 (Figs. 3 and 12) secured on a countershaft 60 also mounted in suitable bearings in the machine frame. In addition to the pulley 58, the countershaft 60 carries a pulley 62 secured thereto which is connected by a belt 64 (Fig. 3) with a pulley 66 on shaft 68 (Fig. 1). The shaft 68 is mounted in bearings in a gear reduction box which is part of a work table supporting assemblage and is arranged for movement heightwise of the machine. In particular, the shaft 68 serves to impart rotary movement to the table 34. Heightwise movement of the shaft 68 with the work table supporting assemblage is permissible without interruption of its driving connection with the countershaft 60 by reason of the belt transmission between the shafts 60 and 68. Secured on the countershaft 60 is a third pulley 70 (Figs. 3 and 12) which is connected by a belt 72 to a pulley 74 mounted on a shaft 76 (Figs. 3, 7 and 13) serving to operate the indenting tool 38.

The above-mentioned pulleys 54 and 58 secured on the main shaft 52 and the countershaft 60, respectively, are of the V-groove type and are adjustable by mechanism to be described to vary

simultaneously the positions radially on the pulleys at which the belt will run in the grooves of the pulleys, thus varying the speed of operation of the entire machine. Moreover, the above-mentioned pulleys 70 and 74 secured to the countershaft 60 and the tool-operating shaft 76, respectively, are also of the V-groove type and are adjustable, by different adjusting mechanism to be described, to vary the speeds of their belt contacting portions so as to vary the speed of operation of only the indenting tool 36, thereby varying the number of indentations provided in the work surface for a predetermined linear distance along the line of feed F.

For the purpose of simultaneously adjusting the speed of the pulleys 54 and 58, there is movably mounted in suitable brackets fixed in the machine frame a pin 78 (Fig. 3) to which sliding movements along its longitudinal axis may be imparted by the manipulation of a treadle rod 80. The upper extremity of the treadle rod is connected to the sliding pin 78 by link and lever mechanism 82 (Fig. 1) engaging a collar 83 on the pin 78. Secured on the sliding pin 78 is a forked arm 84 (Fig. 3) which is in operative engagement with the hub 86 of one half or section of the pulley 54 which half upon movement of the sliding pin 78 is caused to move axially relatively to the opposite half of the pulley 54 so as to vary the peripheral velocity of the belt-engaging portion of that pulley. Another arm 87 (Fig. 1) is secured to the sliding pin 78 operatively to engage one half or section of the pulley 58 so as to cause axial movement of that half relatively to the other half of the pulley 58 on movement of the sliding pin 78 to vary the peripheral velocity of the belt-engaging portion of the pulley 58 simultaneously with the corresponding speed adjustment of the pulley 54.

Considering now more specifically the work table assemblage and its supporting mechanism of which, as stated, the above-mentioned pulley 66 and the table drive shaft 68 are a part at least to the extent of participating in the heightwise movement of that assemblage, it is to be noted that the rotary motion of the shaft 68 mounted in bearings in a reduction gear box 88 (Figs. 1 and 3) is reduced in speed by reduction worm and worm gear mechanism 90 (Fig. 1) housed in the gear box 88.

For the purpose of facilitating heightwise movement of the reduction gear box 88 together with the shaft 68 and pulley 66, the gear box is provided with a sleeve-like guide member 92 (Fig. 3) having a sliding fit on the above-mentioned pin 30 which connects the overhang 26 with the head 24 of the machine.

Mounted in bearings in an upward extension of the gear box 88 is a vertical stub shaft 94 (Fig. 1) which is in driving engagement with the reduction gear mechanism 90 and upon the freely extending upper end of the shaft there is secured a gear 96. The gear 96 is in meshing engagement with a helical gear 98 (Figs. 1 and 5) secured to the lower end of an inclined shaft 100 mounted in suitable bearings in a block 102. The gear mechanism 96, 98 is shielded by a cover 103 (Fig. 3) omitted from Fig. 1. Secured to the upper end of the shaft 100 is the table 34 and, as may be readily seen, there is an uninterrupted train of driving mechanism between the table and the continuously rotating shaft 68.

The table is provided in its upper surface with an annular rubber insert 104 comprising a hard rubber body with a soft rubber top layer protrud-

ing somewhat above the work-engaging surface of the table so as to prevent the tread face of the sole B from being marred by the table when the work is clamped thereagainst, as well as to facilitate the work-feeding operation of the table by providing suitable friction between the table and the work.

The above-mentioned block 102 in which the inclined shaft 100 is rotatably mounted is part of the heightwise movable table assemblage and is connected to the reduction gear box 88 by a curved arm 106 (Figs. 3 and 5). The arm 106 is secured at its upper end to the block 102 by screws 108 and the lower end of the arm 106 is operatively connected to a boss or socket 110 (Fig. 5) provided on the reduction gear box 88. A stud 112 extends through a bore 114 (Fig. 16) in the lower end of the arm 106, the bore being provided with an internal annular flange 116 receiving a head 118 of the stud 112. The lower end of the stud 112 is in threaded engagement with the boss 110. The stud 112 is surrounded by a spring 120 the lower end of which is seated upon a shoulder provided in the socket. The upper end of the spring 120 bears against the annular flange 116. The purpose of this arrangement, as will be readily seen, is to provide a yielding connection between the block 102 supporting the shaft 100 and table 34 on the one hand and the reduction gear box 88 on the other hand. Thus a downward yield of the table 34 relatively to the gear box 88, which is maintained in its elevated position during the entire machine operation, is possible upon increase in work thickness. Should the work thickness decrease the table will automatically adjust itself and rise under the pressure of the spring 120 into its new position to accommodate the work portion of reduced thickness. Moreover, if the gear box, upon release of the treadle, is lowered into its inoperative position, the table is caused to move downward with the gear box due to the engagement of the head 118 of the stud 112 with the top surface of the annular flange 116.

For the purpose of elevating the table-supporting and rotating assemblage comprising the gear box 88, the mechanism housed therein as well as the table 34 and table-supporting block 102, there is mounted in a recess provided in the bottom portion of the gear box 88 a freely rotating roll 122 (Figs. 1 and 3) which is engaged by a cam member 124 pivotally secured on a fixed screw 126, positioned eccentrically relatively to the roll-engaging curved surface of the cam member 124. To rotate the cam member 124 about the pivot screw 126, the cam member is connected by a link 128 to a bell crank lever 130 mounted for rocking movement about a fixed pivot pin 132. A short horizontally extending arm of the bell crank lever 130 is pivotally connected with the upper end of a treadle rod 134 which may be moved heightwise of the machine by a treadle mechanism to be described. Downward displacement of the treadle rod 134 causes a corresponding rocking movement of the cam member 124 about the pivot screw 126 and by reason of the eccentricity of the roll-engaging surface of the cam member 124 with relation to the axis of rotation of the cam member, the gear box 88 and the entire assemblage supported by it, including the work table, are elevated. A spring 136 (Figs. 1 and 3) connecting the treadle mechanism for operating the treadle rod 134 with the top of the lower frame portion 20 serves to elevate the treadle mechanism and to maintain the treadle rod 134 in its uppermost

position with the result that, when inoperative, the table assemblage occupies its lowermost position. In order to determine adjustably the uppermost position of the table assemblage, there is mounted in a bracket secured in the machine head 24 a stop screw 138 (Fig. 1) the lower end of which is engaged by the upper face of the gear box 88 upon elevation of the latter, the screw 138 being so adjusted that even if the table is elevated without a shoe on it, the table cannot foul the indenting tool 36. A spring 140 (Fig. 3) connecting the gear box with the top of the lower frame portion 20 tends to pull the table assemblage into its lowermost inoperative position.

To facilitate heightwise movement of the table-supporting block 102 with the gear box 88 the block is provided with a guideway 142 (Fig. 6) which is engaged by a dovetailed guide member provided on a block 144 (Figs. 3 and 19) secured in the machine head 24.

To prevent a downward yield of the work table 34 under the work impinging impact of the indenting tool and while the latter is pressing against the work, the table is locked against heightwise movement during a certain period of each operating cycle of the machine. To this end, the table-supporting block 102 is provided at its rear face with a recess 146 (Figs. 6 and 19) having side walls 148 that are arranged at an obtuse angle relatively to the bottom of the recess 146 to provide locking surfaces. The recess 146 is engaged by a locking plate 150 mounted for movement relatively to the recess so as to cause either a binding of the angularly disposed edge

faces 152 of the locking plate 150 with the side walls 148 of the recess 146 to prevent heightwise movement of the block 102 or to free the block 102 for heightwise movement. The locking plate 150 is pivotally secured to a locking block 154 mounted for tilting movement on an eccentric portion of a pin 156, the tilting movement of the block 154 in one direction or the other resulting in a locking or unlocking of the table. The pin 156 is held in position in the machine frame by

a set screw 158 illustrated in Figs. 18 and 19. For the purpose of tilting the block 154, it is provided with a rearward extending finger 160. The free end of the finger 160 is engaged in a recess 164 (Fig. 6) provided in a locking pin 162 mounted for vertical sliding movement in a bore provided in the fixed block 144. The locking pin 162 has secured to its upper end a block-shaped head 166 into the upper surface of which is cut a guideway 168 engaged by a hardened steel block 170 which may be adjusted along the guideway and which during a certain period of an operating cycle of the machine is engaged by means to be described for the purpose of depressing the locking pin 162 and releasing the locking plate 150.

The table-locking mechanism is normally held in its operative locking position and to this end, there is provided an axial bore 172 (Fig. 4) in the lower portion of the locking pin 162 and seated in this bore is the upper end of a spring 176. The lower end of the spring rests against a screw 178 threaded into the lower end of the bore in which the pin 162 is movable. It is apparent that the spring tends to displace the locking pin 162 upward thereby rocking the locking block 154 in a counterclockwise direction, as viewed in Fig. 6, so as to move the locking plate 150 into locking engagement with the side walls 148 of the recess 146 provided in the table-supporting block 102. It is furthermore to be noted that the temporary release of the locking mechanism by the

application of pressure to the above-described hardened block 170 is effected against the pressure of the spring 174 and that, as soon as the lock-releasing pressure against the block 170 is removed, the table lock is immediately restored to its operative position by the spring 174.

As previously mentioned, the illustrated machine is provided with a shoe upper guard 38 which simultaneously acts as a shoe gage to determine the heightwise position of the shoe in the machine. This guard and gage mechanism is constructed as follows: A web-like supporting member 178 (Figs. 3 and 4) is mounted for pivotal movement heightwise of the machine on aligned pivot screws 180 secured in a bracket 182 provided on the front cover 28 of the machine. The web-like member 178 carries the above-described plate-like guard member 38 which is made of spring steel and is attached by screws 184 to the web-like supporting member 178. Moreover, the supporting member 178 is provided with spacer screws 186 extending rearwardly therefrom into engagement with a finished surface 188 on the front cover 28 to maintain the web-like member 178 and therefore the guard member 38 supported thereon at a predetermined distance from the finished surface 188 and therefore at a predetermined adjustable position in the machine. The operative position of the guard and gage member 38 may be varied by an adjustment of the spacer screws 186. Moreover, due to the mounting of the supporting member 178 on aligned pivot screws 180, the entire gage and guard mechanism may be swung out of its operative position upward about the common axis of the pivot screws 180 so as to obtain access to the machine parts normally shielded by the guard mechanism.

The above-mentioned indenting tool 36 performs the important function of indenting the protruding marginal portion of the sole or the surface of the welt attached to the sole, if such be the case, by an impinging action on the work surface. The impinging movement of the tool, as will be described, is in a direction both downward and forward toward the work so as to cause the tool to enter deeply into the crease between the welt or sole B and the upwardly extending portion of the shoe upper A, as illustrated in Fig. 9 of the drawings. Moreover, the tool 36 has the function of burnishing the indented portion of the work and, finally, of participating with other work-feeding instrumentalities in the work feed.

For the purpose of imparting work-indenting and work-feeding movements to the tool 36, there is provided an eccentric 190 (Fig. 7 and 13) near the forward end of the shaft 76, this eccentric hereinafter being referred to as the front eccentric. Mounted on the front eccentric 190 is an eccentric strap 192 (Figs. 7 and 13) hereinafter referred to as the front strap. The front strap 192 has a heightwise extending slot 194 which is engaged by a trunnion block 196 rotatably mounted on a fulcrum stud 198. The fulcrum stud is provided at its forward end with a flanged head 200. As will be described, the fulcrum stud 198 is adjustable heightwise to vary the lateral throw of the eccentric strap so as to vary the feed movement of the indenting tool.

To support and operate the indenting tool 36, the front strap 192 has pivotally secured to it a tool-carrying arm 202 (Figs. 4, 7 and 13) provided with a forked end 204 embracing a portion of the strap 192 and being mounted on a sleeve

205 extending through that portion for pivotal movement relatively to the strap and being held in place by a screw 206 extending through the sleeve. The tool-carrying arm 202 has a downward extending projection 208 nearer its freely extending end and this projection 208 is normally held in engagement with an abutment 210 provided on the strap 192 by a spring 212 which connects the free end of the arm 202 with the lower curved end 214 of the strap 192. As will be seen, due to the action of the spring 212, the arm 202 and the front strap 192 move as a unit in an orbital path on rotation of the eccentric 190 and rocking of the front strap 192 about the fulcrum stud 198.

To provide for an adjustment of the tool 36 along the line of feed, the tool is not rigidly mounted on the tool-carrying arm 202 but rather one forked portion of the arm is provided in its outer face with a guideway in which is mounted a sliding member 216 (Figs. 4, 10 and 13), the sliding member 216 having a slot 218 through which the above-mentioned pivot screw 206 extends. Accordingly, the sliding member 216 may be adjusted along the guideway relatively to the arm 202 and may be held in adjusted position by the clamping action of the head of the screw 206 on the member 216. The tool 36 is mounted on the sliding member 216 of the tool-carrying arm 202 in the following manner: The freely extending end of the sliding member 216 is in the shape of a block 220 (Fig. 10). This block 220 is provided with a bore 222 extending at right angles to the vertical plane in the line of feed F (Fig. 1) and mounted in this bore 222 is a pin 224 having a reduced portion 226 (Fig. 8) extending rearward from the block 220 and being provided with a flanged head 228. A forked plate 230 secured to the rear face of the block 220 engages the reduced portion 226 of the pin 224 and serves to hold the pin 224 against the movement lengthwise of the bore 222. The forward extremity of the pin 224 is enlarged and serves as the tool holder proper. It is provided with two spaced vertical flanges 232 between which the indenting tool 36 is mounted to rock on a fulcrum pin in the form of a screw 234 extending through the spaced flanges 232 of the pin 224 and extending through a recess in the lower portion of the indenting tool. The screw 234 is secured in place by a nut 236, as illustrated best in Fig. 10. Secured at one end in a hole through the flanged head 232 of the pin 224 and confined between the right-hand flange 232 (as seen from the front of the machine) and the flanged head of the screw 234 is a torsion spring 238 the other end of which extends upward into engagement with a pin 240 extending laterally from the tool, the spring 238 tending to rock the tool 36 rearward of the machine about the axis of the screw 234. By releasing the screw 234 and nut 236 the tool may be quickly removed from the machine and another tool, designed to produce a different number of indentations per linear unit, may be mounted in the machine.

The pin 224 may rotate in its bore 222 relatively to the block 220 of the sliding member 216 to permit a movement of the tool 36 about the axis of the pin 224 along the line of feed and this possible movement of the tool 36 is primarily intended to compensate for the difference in the rate of feed movement of the tool and other work-feeding instrumentalities. To prevent the tool 36 from rocking freely about the axis of the pin 224, the block 220 is provided above the bore

222 with another bore 242 (Fig. 8) of smaller diameter than the bore 222 and extending parallel thereto. Mounted in the bore 242 is a centering pin 244 which is pressed forward by a spring 246 seated in the bore 242 and engaging the centering pin 244 so that the pin 244 extends outward of the block 220 into a conical recess 248 provided in the rear wall of the enlarged front end of the pin 224. After displacement of the indenting tool 36 along the line of feed relatively to the block 220, the centering pin 244 which has a rounded front end causes, by reason of its cooperation with the conical recess 248, the tool 36 to be returned to its normal vertical position.

As previously explained, the tool-supporting arm 202 is held by the spring 212 in contact with the abutment 210 of the front strap 192 so that normally both the front strap 192 and the arm 202 move as a unit in an orbital path due to the rotary movement of the eccentric 190 and the rocking movement of the front strap about the axis of the fulcrum stud 198. For the purpose of adjustably determining the depth of penetration of the tool into the work surface (indentation depth), a relative movement between the tool-supporting arm 202 and the front strap 192 is brought about toward the end of the downward leg of the orbital movement of the strap 192. To this end, there is provided an adjustable stop 250 (Figs. 4 and 19) to be engaged by the lower portion of the block 228 of the sliding member 216 secured in the arm 202. When on downward movement of the front strap 192 together with the arm 202, the block 228 of the sliding member 216 strikes against the stop 250, the downward movement of the arm 202 and the tool 36 is terminated while the front strap 192 continues its downward movement. As a result of the relative movement between the front strap 192 and the tool-carrying arm 202, the abutment 210 of the front strap becomes separated from the projection 208 of the arm 202. After the front strap 192 has reached the lowest point of its orbital path it immediately begins to rise again due to the continued rotation of the eccentric 190, but the tool-supporting arm 202 only moves again with the front strap 192 as a unit after the abutment 210 of the front strap has reengaged the projection 208 of the arm 202, this taking place some length of time after the front strap has reached its lowest point and has begun to rise again. As will be noted, during the relative movement of the front strap 192 and the tool-carrying arm 202, the front strap 192 when it moves through the lower arc of its orbital path not only moves heightwise of the machine but also laterally thereof along the line of feed so that the arm 202 by reason of its pivotal connection with the front strap 192 is constrained to participate in the latter's lateral movement while the tool 36 is held in engagement with the work. Consequently, the tool is caused to impart a forward movement to the work during and as a result of the lateral movement of the strap 192.

The adjustable stop 250 for the arm 202 is provided on a triangular lever 252 (Fig. 4) which is fulcrumed on a pivot stud 254. One side of the triangular lever 252 is engaged by a wedge 256 which, upon elevation causes the triangular lever to be swung in a counterclockwise direction, as seen in Fig. 4, to move the stop 250 from an inoperative into its operative position which is determined by an adjustable stop pin 258 mounted in the machine frame and engaging a lipped por-

tion of the triangular lever 252. For the purpose of operating the wedge 256 to elevate the stop 250 into its operative position and hold it in that position, the lower end of the wedge 256 has a pin-and-slot connection 262 with a wedge-operating lever 260 pivotally secured on a fixed fulcrum stud 264. Pivotal secured to the wedge-operating lever 260 is a rod 266 which loosely engages a bore 268 (Fig. 17) provided in the above-described reduction gear box 88. The rod 266 is surrounded by a spring 270, the upper end of which bears against a forked head of the rod 266 and the lower end of which is seated in the bore 268 with the result that, upon elevation of the gear box 88 to move the table 34 into its operative position, the lever 260 is yieldingly rotated in a clockwise direction, as seen in Fig. 4, to elevate the wedge 256 which for that purpose is guided for vertical movement in the frame and which thus causes the stop 250 to be moved into its elevated operative position. The purpose of mounting the tool stop 250 to move between an operative and an inoperative position under the control of the work table assemblage is to prevent the tool-supporting mechanism from striking upon the stop while the machine is idling, thereby reducing noise as well as wear and tear.

To release the just-described wedge lock mechanism upon lowering the work table supporting assemblage including the gear box 88, special mechanism, illustrated in Fig. 4, is provided which comprises a bracket 272 secured on the gear box 88 and provided with a horizontal bore in which is received the stem of a stop arm 274 bored to receive a vertical rod 276 provided with a stop nut 278 on its lower extremity and a head 280 at its upper extremity, the head being pivotally secured to the above-mentioned wedge-operating lever 260. As illustrated in Fig. 4, a certain lost motion is provided between the arm 274 and the stop nut 278 on the rod 276. After the arm 274 has traversed this lost motion, on lowering the work table assemblage, it engages the nut 278 and swings the wedge-operating lever downward thus releasing the wedge 256 and causing the stop 250 to drop into its inoperative position. The lost motion is provided primarily to permit small movements of the table supporting assemblage relatively to the wedge lock mechanism without affecting the latter mechanism.

For imparting a burnishing motion to the tool 36 after it has impinged on the portion of the work surface to be indented, the following mechanism is provided: Mounted on the tool-operating shaft 76 is an eccentric 282 (Figs. 7 and 11) located rearward of the above-mentioned front eccentric 190 and hereinafter termed the rear eccentric. The rear eccentric is arranged with its portion of greatest eccentricity disposed diametrically opposite to the corresponding portion of the eccentric 190 and carries a strap 284 hereinafter termed the rear strap. The rear strap 284 has, similarly to the front strap, a heightwise extending slot 286 engaged by a trunnion block 288 which is mounted on the previously mentioned fulcrum stud 198 so that both straps 192 and 284 have a common fulcrum stud. As illustrated best in Figs. 11 and 11a, the rear strap 284 is provided with a boss 290 extending forwardly thereof and supporting a cam block 292 which is secured to the boss by means of a clamping screw 294. The cam block 292 has a cam member 296 against which the indenting tool 36 is held by the above-mentioned torsion spring 238, the cam 296 serving, as the result of the

height-wise movement of the rear strap 284 to impart burnishing movements to the tool 36 in a direction at right angles to the vertical plane in the line of feed F, as will be described.

As stated above, the fulcrum stud 198, carrying the trunnion blocks 196 and 288 is common to both eccentric straps 192 and 286 so that both straps during and as a result of their actuation by the eccentrics 190 and 282 are caused to rock about a common axis in a direction laterally of the machine. In order to change the lateral throw of both straps 192 and 284 the common fulcrum stud 198 is mounted for adjustment heightwise of the machine. It should be noted, also, that in order to maintain a spaced relation between the two eccentric straps a spacer (not shown) is mounted on the fulcrum stud 198 and is located between the two straps. For the purpose of effecting a heightwise adjustment of the fulcrum stud 198, the latter is secured at its rear end in a block 298 (Figs. 3 and 7) the block being guided in a portion of the machine head 24 for vertical movement with relation thereto. The block 298 is provided with a vertically extending tapped bore into which is threaded an adjustment screw 300 (Figs. 3 and 7) carrying at its upper end, a handwheel 302 and being held against vertical movement by a retaining plate 304 secured to the upper portion of the machine head 24. As may be seen, upon rotation of the screw 300 by means of the handwheel 302, the block 298 is adjusted heightwise of the machine and the fulcrum stud 198 accordingly is adjusted simultaneously in the same direction. To prevent the adjustment screw 300 from turning during the machine operation, the screw 300 is engaged by two friction screws 306 (Fig. 3) provided with binding springs and threaded into the block 298.

To vary the speed of the tool-operating shaft 76 for the purpose described, manually operable mechanism, shown best in Fig. 12 of the drawings, is provided. This mechanism comprises a horizontal screw 308 the left-hand end of which is in engagement with a tapped bore provided in a rotatable bearing 310, the remainder of the screw being slidably mounted in different portions of the machine frame. The bearing 310 is provided at its outer forwardly extending stem with a handwheel 312 (Figs. 1 and 12) and the screw is provided at its right-hand extremity with a flanged head 314. The hand wheel 312 and the bearing 310 are immovable in the axial direction of the screw 308 so that upon rotation of the handwheel an axial movement of the screw 308 is produced. Mounted on the screw 308 is a laterally extending arm 316 which participates in the axial movement of the screw 308 upon rotation of the handwheel 312. The arm 316 is in operative engagement with the bearing portion of one half of the previously described pulley 74 on the tool-operating shaft 76 and on movement of the arm 316 axially of the screw this half of the pulley 74 is moved with relation to the other half of the pulley so as to vary the circumferential velocity of the belt-engaging portion of the pulley 74. Similarly, the screw 308 carries another arm 317 (Figs. 3 and 12) which serves to move one half of the pulley 70 relatively to the other half of that pulley to effect a simultaneous adjustment of the speed of its belt-engaging surface with the speed adjustment of the pulley 74.

Adjustment of the common fulcrum stud 198 of both eccentric straps 192 and 284 by the rotation of the handwheel 302 for the purpose of

varying the lateral throw of both eccentric straps and thereby the number of indentations made per linear unit along the line of feed is effected in accordance with a graduated scale (not shown) provided on the machine frame and an index mark or the like (not shown) moving relatively to the scale. This adjustment by the rotation of the handwheel 302 is set proportionately to a simultaneous adjustment of the speed of the tool-operating shaft by means of the handwheel 312, the rotation of the latter being also determinable in accordance with a scale and index mark (not shown). The two scales are alike and may bear consecutive numbers from 8 to 22 which is the usual range of indentations made per inch. If it is desired to increase the number of indentations made for each inch in the line of feed, the handwheel 312 is rotated until its index mark is in register with the number on the scale corresponding to the number of indentations per inch to be made, thereby adjusting the speed of the pulleys 70 and 74 to increase the speed of the belt 72 connecting them and thus to increase the speed of the shaft 76. Simultaneously, the handwheel 312 is rotated until its index mark registers with the same number on its scale, thereby lowering the fulcrum stud 198 and shortening the lateral throw of both eccentric straps. Reversely, if the number of indentations per linear unit is to be reduced, the speed of the belt 72 and therefore of the shaft 76 is reduced by the rotation of the handwheel 312 and, at the same time, the fulcrum stud 198 is elevated to lengthen the lateral throw of both eccentric straps. Due to the provision of these adjustments, it is no longer necessary in the machine of the present invention to exchange the indenting tool for an indenting tool of somewhat different design almost every time a change in the number of indentations per linear unit is to be made. Whereas, in prior indenting machines, at least fifteen different indenting tools are usually required to accommodate a range of indentations from 8 to 22 per inch, only five different tools are required in the present machine so that the frequency of tool exchange typical of the former machines has been reduced about two-thirds.

It will be remembered that the sliding member 216 supporting the indenting tool 36 may be adjusted, by reason of the provision of the slot 218 therein, with relation to the arm 202 and this adjustment is preferably so effected that the tool is located at least in the median vertical plane of the machine, indicated by the line M in Fig. 1, or, preferably, somewhat to the right of that plane (as seen in Fig. 1). This insures that the tool 36 engages the portion of the work which is being supported by the segmental portion of the work table rotating at that time toward its rearmost position in the machine so that the indenting tool in cooperating with that segment of the work table tends to move with the latter rearwardly or inwardly of the machine thereby insuring continuous contact of the work with the gage 38. Otherwise, there may be danger of the work being pushed out of the machine particularly if the tool 36 should exert its indenting pressure upon the portion of the work supported on the segment of the work table rotating at that time away from its rearmost position in the machine. It is to be understood that the work table itself is located in the exact center of the machine, or that, in other words, its axis of rotation coincides with the median vertical plane M of the machine.

Referring now to the presser foot mechanism of the machine which is illustrated in Figs. 1, 2 and 8 of the drawings, it will be noted that the front cover 28 has a bracket 318 (Fig. 8) which is located at the right-hand side of the median interval plane M of the machine. The bracket 318 has a bore 320 the upper end of which is open. A sleeve 324 has a sliding fit in the bore 320 and is provided with diametrically opposite vertical slots 326 through which extends a stud 328, one end of which is secured in the front cover 28 and the other end in the bracket 318, the stud serving to limit heightwise movement of the sleeve 324 with relation to the bracket 318 to the extent of the slots 326. Integral with the lower end of the sleeve 324 is a block 330 and inside of the sleeve there is provided a spring 332 the lower end of which is seated on the top face of the block 330 and the upper end of which engages a recess in the fixed stud 328. Thus, the spring tends to depress the block 330 and sleeve 324 until the upper ends of the slots 326 abut against the pin 328. For the purpose of securing the presser foot 40 to the block 330, the latter is provided with a horizontal bore 334 which is engaged by a stud 336 having at its rear end a bayonet lock 338 engaging a rearward and downward extending portion of the block 330. At its front end, the stud receives a pivot screw 340 by means of which a vertically extending upper portion of the presser foot 40 is pivotally attached to the block 330. The lower portion of the presser foot is inclined outward and toward the left of the machine, as seen in Figs. 2 and 4, so that it extends at an acute angle to the vertical plane in the line of feed F. The pivotal mounting of the presser foot 40 on its supporting block 330 enables the presser foot to participate in the work-feeding movement of the work table against which the presser foot holds the work clamped during a certain portion of an operating cycle. The mounting of the presser foot at the right-hand side of the median vertical plane M of the machine is for the same reason as the adjustment of the indenting tool into a similar position, as previously explained, namely, to enable the presser foot to cooperate in the feeding of the work with the segment of the work table rotating toward its rearmost position in the machine so that the work is held in the machine and not forced out.

To maintain the presser foot 40 in a normal position with relation to the supporting block 330, there is provided a wire spring 342 (Fig. 8), one end of which is clamped to the vertical upper portion of the presser foot by the pivot screw 340 and the other angularly deflected end of which extends into a vertical groove 346 (Figs. 8 and 11) provided in a block 344 which is integral with the previously mentioned cam block 292. The block 344 is located beneath the lower face of the presser foot supporting block 330 and, during the upward movement of the rear strap 284 and the concomitant elevation of the block 344, the latter is caused to engage the block 330 and move it together with the presser foot 40 into an elevated, inoperative position. As may be seen, as soon as the rear strap 284 begins to descend, the spring 332 is freed to lower the block 330 and the presser foot 40 into their lowermost operative positions in which the work is clamped against the work table by the presser foot.

Owing to the fact that the two eccentrics 190 and 282 are arranged diametrically opposite to each other, one of the straps is on its downward

stroke when the other is on its upward stroke and vice versa so that, e. g., on elevation of the presser foot into its upper inoperative position by the eccentric strap 284, the indenting tool 36 is lowered upon the work by the eccentric strap 192 and that on elevation of tool 36 the presser foot 40 is lowered. Thus, the work is continuously clamped against the work table by either the indenting tool or the presser foot and hence, a continuous feed movement is imparted to the work during the continuous rotation of the work table 34.

Referring to Figs. 4, 7, 11 and 11a of the drawings, it will be noted that the boss 290 of the rear strap 284 has a downwardly extending bracket 348 provided in its lower surface with a groove 350 in which is received a block 352 pivotally secured on a pin 354 fastened in the bracket 348. The lower portion of the block 352 is connected by a spring 356 with a pin fixed in the bracket 348 the spring tending to hold the upper portion of the block against the bottom of the groove 350 so that block 352 and rear strap 284 normally move as a unit. Threaded into the lower portion of the block 352 is a frusto-conical screw stud 358 which, upon downward movement of the rear strap 284, is caused to strike upon the above-mentioned hardened steel block 170 (Fig. 6) to depress the locking pin 162 and release the locking plate 150 against the pressure of the spring 174. It is to be noted that the table-locking mechanism is released, as stated, on downward movement of the rear strap 284, this movement also permitting the presser foot to clamp the work against the rotary table under the action of the spring 332. While this takes place, the tool-supporting front strap 192 is on its upward stroke and elevates the tool into its upper inoperative position. When thereafter the tool is moved into engagement with the work as a result of the downward movement of the front strap 192, the screw stud 358 is elevated by the rear strap 284 to cause the table 34 to be automatically locked again by the spring 174.

The purpose of mounting the screw stud 358 on the block 352, movable relatively to the rear strap 284 but normally held by the spring 356 to move with the strap 284 as a unit, is to prevent breakage of the machine parts if for some reason the driving mechanism of the machine should be reversed; in which case the screw stud 358 would abut against the end of the steel block 170 from which in the normal operation it slides off or snaps off, without being able to rise on top of the block 170 which is normally maintained in its elevated position by the spring 174.

As has been explained above, the welt-indenting tool 36 of the present machine is moved into engagement with the work as a result of the downward movement of the front strap 192 which is actuated to move continuously in an orbital path. As a result of the work-impinging action of the tool, it is caused to penetrate the work surface to a predetermined depth of about $\frac{1}{2}$ of an inch and its further downward movement is then prevented by reason of the engagement of the tool-carrying slide 216 with the stop 250, while the eccentric strap 192 continues its downward movement. The tool remains in engagement with the work while the strap 192 moves through the lower arc of its orbital path. The tool-carrying arm 202 and the strap 192 again move as a unit after the re-engagement of the abutment 210 with the projection 208. During the relative movement of the tool-carrying arm

202 and strap 192, the tool 36 is caused to move in the line of feed because the tool-carrying arm 202 is constrained to move laterally with the strap 192, it being pivotally secured at 206 to the strap. It has been explained furthermore that the rear strap 284 performs three important functions, namely, that of permitting the presser foot to engage the work during a predetermined period of time in one operating cycle, that of releasing the table lock during a predetermined period of time in one operating cycle, and that of imparting burnishing movements to the tool 36 while the latter is in engagement with the work as well as causing the tool when being moved into engagement with the work to follow a downwardly inclined path so as to cause the tool to move into the so-called welt crease of the shoe. Moreover, it has been stated that, since the two eccentrics 190 and 282 are angularly displaced 180°, the two straps 192 and 284 are caused to move in opposite directions heightwise of the machine so that the indenting tool 36 is moved into engagement with the work when the presser foot 40 is elevated into its inoperative position and the table locking spring 174 is permitted to lock the work table assemblage in operative position.

As illustrated best in Fig. 9 of the drawings, the previously mentioned cam 296 supported on the rear strap 284 cooperates with a rearwardly extending hump portion of the indenting tool 36 in bringing about an engagement of the indenting tool 36 deep in the welt crease on downward movement of the tool as well as causing, by reason of the movements of both the tool 36 and the cam 296 heightwise of the machine in opposite directions, repeated burnishing movements of the tool while the latter is engaging the work, as will be described.

As stated, the indenting tool 36 and the presser foot 40 cooperate with the work table 34 in feeding the work substantially at different periods during one cycle. However, there is a slight overlap of work engagement at the beginning and termination of the work feeding motion of each instrumentality. In particular, the arrangement is such that, assuming a new cycle of operation starts upon engagement of the indenting tool 36 with the work surface, the tool has reached its indentation depth after about 15° of rotation of the tool operating shaft 76 from its zero position. Thereupon the tool remains in engagement with the work, i. e., at the level of the indentation depth, until the shaft has been rotated about 195°, the tool then being elevated but not yet losing contact with the work until the shaft 76 has been rotated about 210°. This indicates that the indenting tool 36 remains in actual contact with the work for 210° of one cycle. The presser foot 40 which at the beginning of the cycle is in contact with the work is lifted from the work at about 30° of the cycle and remains out of contact with the work until the shaft 76 has reached 180° of the cycle. This indicates that the work contacting periods of the indenting tool and the presser foot overlap at the beginning and the end of the work-feeding movement of each instrumentality and, as described, this overlap occurs substantially during the period extending between 0° and 30° of the cycle as well as the period extending between 180° and 210° of the cycle. It will be understood that by reason of the alternate cooperation of the indenting tool 36 and the presser foot 40 with the continuously rotating work table 34 and the fact

that the different periods of cooperation of both tools with the work table overlap to some extent during the entire 360° of one cycle, a continuous feed movement is imparted to the work.

5 Substantially at the same time, when the tool 36 begins to move upward out of its indentation position, which is as stated, at approximately 195° of a cycle, the screw bolt 358 as a result of the then downward movement of the rear strap 284 engages the hardened steel block 170 releasing the locking plate 150 and thus permitting free heightwise movement of the work table supporting assemblage. This condition obtains until the tool-operating shaft 76 has 15 reached 345° of one cycle at which time the screw bolt 358 rides off one edge of the block 170 causing an abrupt and immediate relocking of the table in its operative position, the table remaining locked until during the next cycle the shaft 20 276 has again been rotated through to 195°.

Considering briefly the burnishing action of the cam 296 on the tool 36 during the movements of both straps 192, 284 in opposite directions, it is to be noted that when the tool 36 occupies its uppermost inoperative position, the cam 296 occupies its lowermost position, as illustrated in dash lines in Fig. 9. The position of the tool and the cam at the time of work engagement of the tool is illustrated in Fig. 9 in full lines. The position of

25 the tool after having reached the indentation depth and the corresponding position of the cam 296 is illustrated in Fig. 9 in dot and dash lines. When the tool is in its uppermost position, its rearmost hump portion is located above and at 35 the rear of the foremost portion of the cam 296, the tool being held in this position by the spring 238. Consequently, when the tool is then moved downward and the cam 296 moved upward, the tool is cammed forward until the foremost portion 40 of the cam 296 is cleared by the tool, it being understood that the cam 296 at all times moves substantially in a vertical plane parallel to the line of feed. As illustrated best in Fig. 11, the cam 296 is of sufficient extent transversely of the

45 machine to maintain contact with the tool 36 in spite of the lateral motions of both straps 192 and 284. When the tool has reached its work-engaging position and immediately thereafter its indentation position, the tool is located foremost 50 of the machine because in this position, the rearmost portion of the tool hump and the foremost portion of the cam 296 are in contact with each other (see full lines in Fig. 9). Thereafter, the cam 296 continues to move upward while the tool

55 is held immovable heightwise of the machine, a flat portion of the cam 296 then engaging a flat portion of the tool 36 with the result that the tool is permitted to be moved by the spring 238 rearward of the machine while remaining in engagement with the work, thereby causing the indented portion of the work to be burnished. Thereafter, due to the reversal of the movement of the two straps 192, 284, the cam 296 is again moved downward 60 while the tool is still held immovable heightwise of the machine (the abutment 210 of the strap 192 not yet having reengaged the projection 208 because this requires a certain amount of movement of the strap 192 upward from its outermost position). By reason of this downward movement of the cam 296 relatively to the tool 36, the foremost portion of the cam 296 again is caused to approach the rearmost portion of the tool 36 with the result that the tool 36 is again forced outward of the machine to its outermost

65 position thus performing another burnishing or

70 75

rubbing action on the same indented portion of the work whereupon the tool is raised from the work by the continued upward movement of the front strap 192. Thus each indented portion of the shoe sole B is burnished twice before the tool can indent a contiguous portion of the work.

The illustrated machine has, as previously described, two different treadle rods 80 and 134 of which one serves to vary the speed of rotation of the countershaft 60 and the other one serves to elevate the work table supporting assemblage into its operative position. It is conceivable for purposes of more general consideration of this feature of the invention that the two treadle rods could be employed to perform other operations than those described above. Both rods may be operated either simultaneously or separately or successively in a certain order or in the reverse of that order by a single treadle mechanism. This treadle mechanism is illustrated best in Fig. 15 of the drawings and reference may also be had to Figs. 1 and 3. The treadle mechanism comprises a Y-shaped frame or web 360, a portion of which is in the form of a cradle or bearing 361. The Y-shaped frame 360 is mounted for rotary motion heightwise of the machine on a fixed bracket 362 by means of aligned fulcrum studs 364 (Fig. 15). The treadle rod 134 has a forked lower end 366 (Fig. 3) which is pivotally secured to the frame 360 by a pivot screw 368 (Fig. 15) to swing the Y-shaped frame 360 about the fulcrum studs 364. The frame 360 is provided with a tread plate 370 upon the depression of which the frame 360 is swung downward and the treadle rod 134 is moved downward so as to elevate the work table 34 supporting assemblage. The aforementioned spring 136 serves to maintain the Y-shaped frame 360 in an elevated position, the lower end of the spring 136 being secured to the frame 360 and the upper end being secured to the top of the lower frame portion 20. The tread plate 370 is secured to the forward end of a treadle member in the form of a shaft 372 which is mounted for rotary motion about its own longitudinal axis in bearings 374 as well as in the cradle 361, provided on the Y-shaped frame 360. Secured to the rear portion of the shaft 372 is a laterally extending arm 376, the free end of which is fork shaped and carries a swivel block 378 secured to it by a swivel pin 380, the lower end of the treadle rod 80 being threaded into the swivel block. As may be seen, rocking motion of the shaft 372 in one direction or the other as a result of a tilting movement imparted to the tread plate 370 will cause a swinging movement of the arm 376 about the axis of the shaft 372 and produce a corresponding upward or downward movement of the treadle rod 80 so as to increase or decrease the speed of the countershaft of the machine. To hold the treadle rod 80 and arm 376 normally elevated the lower portion of the rod 80 is engaged by the lower end of a spring 381, the upper end of which is secured to the top of the frame portion 20. To limit the rocking motion of the shaft 372 in either direction, the forward portion of the shaft is provided with a split collar 382 (Figs. 14 and 15) secured to the shaft by a clamping screw 384. The collar carries on a rearwardly extending plate two stop screws 386 which are arranged alternately to engage a flat surface on the foremost bearing 374 of the shaft 372 to limit rotary motion of the shaft in both directions.

The operation of the machine will be apparent from the foregoing description but may be sum-

marized as follows: A shoe, the sole or welt of which is to be indented, is placed upon the slightly inclined work table 34 in such a position relative to the operating instrumentalities of the machine that the indenting operation will begin at the heel breast line at one side of the shoe and will proceed from there along that side toward the toe end, around the toe portion and back along the other side of the shoe toward the heel breast line. By the depression of the tread plate 370 and the frame 360 of the treadle mechanism, the work table 34 with the shoe thereon is elevated into its operative position until the top face of the welt or the projecting margin of the outsole engages the shoe upper guard 38.

The principal happenings during one cycle of operation beginning with the descent of the tool into engagement with the work are as follows: As a result of the downward movement of the front strap 192, the tool is caused to impinge upon the work until it has reached its predetermined indentation depth after which there is no further downward movement of the tool owing to the engagement of the stop 258 with the tool-supporting sliding member 216. During this downward movement of the front strap 192, the rear strap 284 is moving upward with the result that the spring 174 of the table-locking mechanism is free to lock the work table in its operative position against the impinging action of the indenting tool 36 on the work. Furthermore, the upward movement of the rear strap 284 causes the elevation of the presser foot 40 into its inoperative position as described. While the indenting tool 36 remains in engagement with the work during the relative movement of the tool-supporting arm 202 and the front strap 192, the latter during that period moving through the lower arc of its orbital path, burnishing movements in a direction at right angles to the vertical plane through the line of feed F are imparted to the tool by the cam 296 supported on the rear strap 284, the burnishing movements being the result of the opposite movements of both straps 192 and 284 heightwise of the machine as well as the peculiar configuration of the cam-engaging portion of the tool 36 and of the cam 296. The tool, after having indented and burnished a portion of the work and by reason of the lateral movement of the strap 192 in the line of feed having been moved in that direction while pressing the work against the continuously rotating work table 34 and thereby having imparted a feed movement to the work, is elevated in the general direction of the path of its descent as soon as the now upwardly moving front strap 192 causes its abutment 210 to re-engage the projection 208 of the tool-supporting arm 202. During this upward movement of the front strap 192 the rear strap 284 moves downward and, consequently, the presser foot is permitted to come down upon the work to continue the latter's feed movement by pressing the work against the work table and moving with the work table substantially in the line of feed. At the same time, the downward movement of the rear strap 284 causes a release of the table lock by the engagement of the screw stud 358 with the hardened steel block 179 of the table lock releasing mechanism. As a consequence of the release of the table lock, the work table 34 upon variation of the work thickness may automatically adjust itself heightwise, it being understood that the continued depression of the treadle maintains the table-supporting assemblage in its uppermost position during the

entire machine operation. Thereafter, the movement of the two straps 192, 284 is reversed, the indenting tool again descending to engage a new portion of the work and the presser foot moving into its inoperative elevated position, while at the same time, the spring 174 is again released to lock the work table in its operative work-sustaining position.

Having thus described my invention, what I claim as new and desire to secure by Letters Patent of the United States is:

1. In an indenting machine, an indenting tool, a support for the indenting tool, and an eccentric for moving the tool support in a closed orbital path to impart to the tool a work indenting and a work feeding motion.
2. In an indenting machine, an indenting tool, a support for the indenting tool, a continuously rotating shaft, and an eccentric on the shaft for moving the tool support in a closed orbital path to impart to the tool a work indenting and a work feeding motion.
3. In an indenting machine, an indenting tool, a support for the indenting tool, an eccentric for moving the support in a closed orbital path to cause the tool to move bodily heightwise and transversely of the machine so as to indent the work and move in the direction of work feed.
4. In an indenting machine, an indenting tool, a support for the indenting tool, a continuously rotating shaft, and an eccentric on the shaft for moving the tool support in a closed orbital path to cause the tool to move bodily heightwise and transversely of the machine so as to indent the work and move in the direction of work feed.
5. In an indenting machine, an indenting tool, a support for the tool, an eccentric for moving the support in an orbital path, a tool-carrying member mounted on the support for movement relatively thereto, and means acting on the member and tending to cause both the support and the member to move as a unit.
6. In an indenting machine, an indenting tool, a support for the tool, an eccentric for moving the support in an orbital path, a tool-carrying member mounted on the support for movement relatively thereto, spring means acting on the member and tending to prevent movement of the member relatively to the support, and a stop for said member active when engaged by the latter to cause relative movement between the member and the support.
7. In an indenting machine, a work support, an indenting tool, a tool support, eccentric means for continuously moving the tool support in a closed orbital path heightwise and transversely of the machine, a tool carrying arm pivotally mounted on the support, spring means tending to prevent relative movement between the arm and the support, and an adjustable stop active on the downward movement of the support to engage the arm and terminate its downward movement while permitting continued downward movement of the support so as to determine the length of the downward stroke of the tool and the depth of the work indentation produced by it.
8. In an indenting machine, a work support, an indenting tool, a tool support, eccentric means for continuously moving the tool support in a closed orbital path heightwise and transversely of the machine, a tool-carrying arm pivotally mounted on the support and spring-biased to participate in the movement of the support, a stop active on downward movement of the tool support to engage the arm and to terminate the downward movement of the tool after the latter has engaged the work and penetrated its surface to a predetermined indentation depth, the continued orbital movement of the tool support serving to move the arm transversely of the machine to impart to the tool a work feeding motion.
9. In an indenting machine, a work support, an indenting tool, a continuously rotating shaft, an eccentric on the shaft, an eccentric strap actuated by the eccentric, a tool-carrying arm mounted on the strap for movement relatively thereto, means for normally preventing relative movement between the strap and the arm, and a stop for engaging the arm once during each cycle of the eccentric to cause relative movement between the arm and the strap and to locate the tool at a predetermined position relatively to the work on the work support.
10. In an indenting machine, a work support, an indenting tool, a continuously rotating shaft, an eccentric on the shaft, a tool-supporting strap actuated by the eccentric to impart work-indenting and work-feeding motions to the tool, another eccentric on the shaft, a second strap actuated by the last-mentioned eccentric, and a tool-engaging cam on the second strap for imparting a burnishing motion to the tool.
11. In an indenting machine, a work support, an indenting tool, a continuously rotating shaft, an eccentric on the shaft, a tool-supporting strap actuated by the eccentric to impart work-indenting and work-feeding motions to the tool, a second eccentric on the shaft and disposed diametrically opposite the first-mentioned eccentric, a second strap actuated by the second eccentric member, and a cam mounted on the second strap for imparting repeated burnishing motions to the tool during each cycle of operation.
12. In an indenting machine, an indenting tool, a continuously driven eccentric strap for imparting work-indenting and work-feeding motions to the tool, the strap carrying a fulcrum pin for the tool disposed parallel to the vertical plane in the line of feed, and means for oscillating the tool about said pin to burnish the work.
13. In an indenting machine, an indenting tool, a continuously driven eccentric strap supporting the tool and imparting to it work-indenting and work-feeding motions, a second continuously driven eccentric strap carrying a cam engaging the tool and imparting burnishing movements thereto, and a common fulcrum stud about which both straps are rocked.
14. In an indenting machine, a work support, means for adjusting the work support heightwise of the machine, means for locking the work support in adjusted position, an indenting tool, a continuously driven eccentric strap supporting the tool and imparting to it work-indenting and work-feeding movements, a second continuously driven eccentric strap carrying a cam engaging the tool and imparting burnishing movements thereto, and means carried by the second strap for intermittently releasing the said locking means.
15. In an indenting machine, an indenting tool, a continuously driven eccentric strap supporting the tool and imparting to it work-indenting and work-feeding motions, a second continuously driven eccentric strap carrying a cam engaging the tool and imparting burnishing motions thereto, a common fulcrum stud about which both straps are rocked, and means for adjusting the fulcrum stud in a direction heightwise of the machine.

16. In an indenting machine, a rotary work table, means for rotating the work table at a constant peripheral velocity, an indenting tool, a support for the indenting tool, means for moving the support downward to cause the tool to clamp the work against the table and for moving the support transversely of the machine to cause the tool to cooperate with the table in feeding the work, the tool being movable relatively to the support to compensate for any difference in the rates of speed of the table and the support.

17. In an indenting machine, a rotary work table, means for rotating the work table at a constant peripheral velocity, an indenting tool, a support for the indenting tool, means for moving the support downward to cause the tool to clamp the work against the table and to indent the surface of the work and for moving the support transversely of the machine to cause the tool to cooperate with the table in feeding the work, a pin carried by the tool support and extending at right angles to the vertical plane in the line of feed, a tool holder rotatable about said pin to compensate for any difference in the rates of speed of the table and the tool support, a fulcrum pin for the tool secured in said tool holder, and means for oscillating the tool about said fulcrum pin to cause the tool to burnish the indented portion of the work.

18. In an indenting machine, a work support, an indenting tool, a continuously rotating shaft, an eccentric on the shaft, a tool-supporting strap actuated by the eccentric to impart work-indenting and work-feeding motions to the tool, another eccentric on the shaft, a second strap actuated by the last-mentioned eccentric, a tool-engaging cam on the second strap for imparting burnishing movements to the tool, and spring means tending to maintain the tool in contact with the cam.

19. In an indenting machine, a work support, an indenting tool, a support for the indenting tool, means for moving the tool support in a direction heightwise of the machine to cause the tool to indent the work, a cam for engaging the tool and imparting burnishing movements thereto, means for moving the cam heightwise of the machine and in a direction opposite to the movement of the tool support.

20. In an indenting machine, a rotary work table, means for rotating the work table at a constant peripheral velocity, an indenting tool, a support for the indenting tool, means for moving the tool support downward to cause the tool to clamp the work against the table and for moving the tool support transversely of the machine to cause the tool to cooperate with the table in feeding the work, a pin secured in the tool support about which pin the tool is movable along the line of feed, and spring means tending to hold the tool in a substantially vertical position.

21. In an indenting machine, a work support, means for adjusting the work support heightwise of the machine, means for locking the work support in adjusted position, an indenting tool, a continuously driven eccentric strap supporting the tool and imparting to it work-indenting and work-feeding movements, a second continuously driven eccentric strap carrying a cam for engaging the tool and imparting burnishing movements thereto, and means movably mounted on the second strap for intermittently releasing the said locking means.

22. In an indenting machine, a work support,

means for adjusting the work support heightwise of the machine, means normally operative to lock the work support, an indenting tool, a support for the indenting tool, means for moving the tool support downward to cause the tool to indent the work, means for releasing the said locking means, a support for the lock releasing means movable in a direction opposite to the movement of the tool support so as to release the lock upon elevation of the tool.

23. In an indenting machine, a rotary work table, means for rotating the work table at a constant peripheral velocity, an indenting tool, a support for the indenting tool, a presser foot mounted for movement heightwise and transversely of the machine, and spring means for depressing the presser foot to hold the work against the table thereby imparting a feed movement to the work.

24. In an indenting machine, a rotary work table, means for rotating the work table at a constant peripheral velocity, an indenting tool, a support for the indenting tool, a presser foot mounted for movement heightwise of the machine and along the line of feed, spring means for depressing the presser foot to clamp the work against the table and to participate in the work feeding movement of the table, and spring means for returning the presser foot to its initial position along the line of feed.

25. In an indenting machine, an indenting tool, a support for the indenting tool movable heightwise and transversely of the machine, means for lowering the support during a portion of an operating cycle to cause the tool to clamp the work against the table and to cooperate with the table in feeding the work, a presser foot mounted for movement heightwise and transversely of the machine, means for lowering the presser foot during another portion of the same operating cycle for the purpose of causing the presser foot to clamp the work against the table and to continue its feed movement during the last-mentioned portion of the operating cycle.

26. In an indenting machine, a continuously rotating work table, an indenting tool, and a presser foot, the tool and the presser foot alternately cooperating with the work table during a complete cycle of operation to cause a continuous feed of the work through the machine.

27. In an indenting machine, an indenting tool, a support for the indenting tool, means for moving the tool support downward to impart to the tool a work indenting and a work feeding motion during a certain period of one cycle, a presser foot mounted for heightwise movement in the machine, yielding means tending to lower the presser foot, and positively operated means for elevating the presser foot during the work-feeding period of the tool.

28. In an indenting machine, a continuously rotating work table, an indenting tool actuated to clamp the work against the work table during a predetermined portion of an operating cycle so as to feed the work, a presser foot actuated to clamp the work against the table during another predetermined portion of the same operating cycle so as to participate in the feed of the work, the movements of the tool and the presser foot in the direction of feed being so timed as to overlap.

29. In an indenting machine, an indenting tool movable heightwise and transversely of the machine, means for imparting a work feeding mo-

tion to the indenting tool after it has engaged the work, a positively rotated work table a presser foot movable heightwise and transversely of the machine, and means for causing the presser foot to be rendered operative to cooperate with the work table so as to participate in the feed of the work immediately prior to the termination of the work-feeding motion of the tool.

30. In an indenting machine, a continuously rotated work table, an indenting tool, a continuously driven eccentric strap for imparting work-indenting and work-feeding motions to the tool, a presser foot movable heightwise and transversely of the machine, yielding means for lowering the presser foot to cooperate with the work table in feeding the work, a second continuously driven eccentric strap carrying a cam for elevating the presser foot during a substantial portion of the feed movement of the tool.

31. In an indenting machine, a continuously rotated work table, an indenting tool, a continuously driven eccentric strap for imparting work-indenting and work-feeding movements to the tool, a presser foot movable heightwise and transversely of the machine, yielding means for lowering the presser foot to cooperate with the work table in feeding the work, a second continuously driven eccentric strap carrying a cam for both elevating the presser foot during a substantial portion of the feed movement of the tool and for reciprocating the tool in a direction at right angles to the line of feed to burnish the indented portion of the work.

32. In an indenting machine, a continuously rotated work table, means for adjusting the work table heightwise in the machine, means for locking the work table in adjusted position, an indenting tool, a support for the indenting tool, means for moving the support heightwise of the machine to impart to the tool a work indenting and a work feeding motion, a presser foot movable heightwise of the machine, a second support movable heightwise of the machine in a direction opposite to the first-mentioned support, a cam on the second support for both elevating the presser foot during a substantial portion of the feed movement of the tool and imparting burnishing movements to the tool, and a lock-releasing mechanism on the second support operative to release the lock upon elevation of the tool.

33. In an indenting machine, an indenting tool, a support for the indenting tool, eccentric means for continuously moving the tool support in a closed orbital path heightwise and transversely of the machine to impart to the tool a work indenting and a work feeding motion, a tool-carrying arm movably mounted on the support, and a guideway in said arm along which the tool is adjustable in the line of feed.

34. In an indenting machine, a work gage, an indenting tool, a support for the indenting tool, eccentric means for continuously moving the tool support in a closed orbital path heightwise and transversely of the machine to impart to the tool a work indenting and a work feeding motion, a tool-carrying arm movably mounted on the support, a guideway in said arm along which the tool is adjustable in a direction opposite to the direction of feed to assume a work engaging position beyond the vertical median plane of the machine so as to enable the tool in cooperation with the work table to force the work against the work gage.

35. In an indenting machine, a rotated work

table having its center of rotation located in the vertical median plane of the machine, a work gage, an indenting tool, a support for the indenting tool movable heightwise of the machine to

5 cause the tool to indent the work and movable transversely of the machine to impart to the tool a work feeding motion during one portion of a cycle, a presser foot movable heightwise and transversely of the machine, and spring means 10 for depressing the presser foot to clamp the work against the rotated table so as to cooperate with the table in imparting a feed motion to the work during another portion of the same cycle, the presser foot engaging the work at one side of the 15 said median plane so as to tend to force the work against the work gage.

36. In an indenting machine for operating on welted shoes, an indenting tool, means for moving the indenting tool into the welt crease to indent the welt, a guard for protecting the shoe upper against the tool and for determining the heightwise and horizontal position of the shoe, and means for adjusting the guard heightwise of the machine.

20 37. In an indenting machine for operating on welted shoes, an indenting tool, means for moving the indenting tool into the welt crease to indent the welt, a guard for protecting the shoe upper against the tool and for determining the heightwise and horizontal position of the shoe, the guard comprising a pivotally mounted web carrying a plate of spring steel adapted to engage the shoe upper, and means for adjusting the web heightwise of the machine.

38. In an indenting machine, an indenting tool, a movable work support assemblage comprising a rotary work table and mechanism for rotating the table, a cam for moving the assemblage into operative position, and treadle-controlled means 40 for operating the cam.

39. In an indenting machine, an indenting tool, a movable work support assemblage comprising a rotary work table and mechanism for rotating the table, a cam for moving the assemblage into operative position, treadle-controlled means for operating the cam, and spring means tending to move the assemblage into its inoperative 45 position.

40. In an indenting machine, an indenting tool, 50 a frame portion, an overhang on said frame portion, a pin for connecting the overhang with the frame portion, a work support assemblage movable heightwise of the machine along said pin and comprising a rotary work table and means 55 for rotating the table, and treadle-controlled cam means for moving the assemblage into operative position.

41. In an indenting machine, an indenting tool, a work support assemblage comprising a rotary 60 work table and means for rotating the table, a cam for moving the assemblage into operative position, treadle-controlled means for operating the cam, and means for locking the work support assemblage in operative position.

65 42. In an indenting machine, an indenting tool, means for operating the tool, a movable work support assemblage comprising a rotary work table and means for rotating the table, treadle-controlled cam means for moving the assemblage into operative position, means for locking the assemblage in operative position, and means actuated by the tool operating means for intermittently releasing the locking means.

70 43. In an indenting machine, an indenting tool, a support for the indenting tool, a tool-

carrying arm movably mounted on the support, a movable stop for terminating movement of the arm into operative position, and means for moving the stop into operative position.

44. In an indenting machine, a work support movable heightwise of the machine into operative position, an indenting tool, a support for the indenting tool, a tool-carrying arm movably mounted on the tool support, a movable stop member for terminating the movement of the arm into operative position, means active in response to heightwise movement of the work support to move the stop into operative position.

45. In an indenting machine, a work support movable heightwise of the machine into operative position, an indenting tool, a support for the indenting tool, a tool-carrying arm movably mounted on the tool support, a movable stop member for terminating the movement of the arm into operative position, means active in response to heightwise movement of the work support to move the stop into operative position, and means for adjustably determining the operative position of the stop.

46. In an indenting machine, a work support movable heightwise of the machine into operative position, an indenting tool, a support for the indenting tool, a tool-carrying arm movably mounted on the support, a pivoted stop member, an adjustable stop screw for determining the operative position of the stop member, a wedge member for moving the stop member into operative position, and yieldingly operating connections between the work support and the wedge member for actuating the wedge member on heightwise movement of the work support.

47. In an indenting machine, a work support movable heightwise of the machine into operative position, an indenting tool, a support for the indenting tool, a tool-carrying arm movably mounted on the support, a pivoted stop member, an adjustable stop screw for determining the operative position of the stop member, a wedge member for moving the stop member into operative position, yieldingly operating connections between the work support and the wedge member for actuating the wedge member on elevation of the work support, and means active on lowering the work support to release the wedge member to permit the stop member to move away from the stop screw.

48. In an indenting machine, a frame, an indenting tool, a rotary work table, a table support movable relatively to said frame, mechanism contained in said support for rotating the table, and yielding means connecting the table with the support.

49. In an indenting machine, an indenting tool, an eccentric strap for supporting the tool

and imparting to it work-indenting and work-feeding motions, a shaft for actuating the eccentric strap, a fulcrum stud about which the strap is caused to rock during its actuation, means for varying the speed of the shaft, and means for varying the heightwise position of the fulcrum stud in accordance with the adjustment of the speed of the shaft, thereby varying the rate of feed of the work and the number of indentations made for a predetermined linear distance on the work along the line of feed.

50. In a machine for operating on work parts, a work support, operating instrumentalities, means for driving the operating instrumentalities, a treadle comprising a treadle arm and a tread plate, and movable about one axis to elevate the work support and movable about another axis to vary the speed of operation of said driving means.

51. In a machine for operating on work parts, a treadle for controlling the operation of the machine comprising a tread plate secured to a treadle arm, the treadle arm being mounted for bodily movement about a fixed axis to perform one operation and being mounted for rotary movement about its own longitudinal axis to perform another operation.

52. In a shoe machine, a shoe support, means for operating on a shoe, means for driving the operating means, a treadle comprising a tread plate secured to a treadle arm and mounted to rotate independently about two axes disposed angularly with relation to each other so as to control the operation of the shoe support as well as the operation of the said driving means.

53. In a shoe machine, a movable shoe support, means for operating on a shoe, means for driving the operating means, and a treadle having a single treadle arm for moving the shoe support as well as controlling the speed of operation of said driving means.

54. In a shoe machine in which a plurality of operations are performed, a treadle comprising a heightwise movable frame, aligned bearings in the frame, a cylindrical treadle member rotatably mounted in the bearings, and a tread plate mounted on the treadle member adapted to move the frame heightwise to perform an operation and to rotate the treadle member relatively to the frame to perform another operation.

55. In a shoe machine in which a plurality of operations are performed, a treadle comprising a heightwise movable support and a treadle arm movable relatively to the support, and a tread plate secured to the treadle arm and adapted to move the support heightwise to perform an operation and to move the treadle member relatively to the support to perform another operation.

ROBERT N. SANDBERG.

CERTIFICATE OF CORRECTION.

Patent No. 2,377,377.

June 5, 1945.

ROBERT N. SANDBERG.

It is hereby certified that error appears in the printed specification of the above numbered patent requiring correction as follows: Page 8, first column, line 6, for "interval" read --vertical--; and that the said Letters Patent should be read with this correction therein that the same may conform to the record of the case in the Patent Office.

Signed and sealed this 9th day of October, A. D. 1945.

Leslie Frazer

(Seal)

First Assistant Commissioner of Patents.
